WELDED BITUBULAR COLUMN

Lawrence Lee Schauer, Wyoming, Ohio, assignor
to The Cincinnati Bickford Tool Company, Cincinnati, Ohio, a corporation of Ohio

Application September 17, 1935, Serial No. 40,910

9 Claims. (Cl. 77—28)

The invention relates to improvements in columns for drilling machines and more particularly to a welded bi-tubular column.

The invention has great utility in the construction and operation of radial drilling machines, for in such machines, the column is the fulcrum point of a massive radial arm frequently ten feet or more in length, upon which is mounted a translatable drill head weighing upward of a half-ton. In some constructions a sleeve member is interposed between the arm and the column, whereas in other constructions no sleeve is used. However, in either type the column necessarily must be massively proportioned to carry the load of the sleeve, the radial arm, and the tool head, without flexing or yielding in any way.

Any yielding of the column at the lower regions near its base naturally introduces an error in alignment which is magnified over and over again in the alignment of the tool spindle that is journaled in the head out on the arm.

To meet that condition the cast iron columns heretofore used were, with due regards to the unit strength of cast iron, made exceedingly large and very heavy. And although manufacturing, transportation, and selling considerations required that the column be constructed with the least amount of material consistent with the rigidity and accuracy demanded in the completed machine, the huge cast iron columns of the machines represent still too large a proportion of the cost of the completed machine.

The primary object of the present invention is to render available a column having the strength and rigidity necessary to withstand the severe bending loads of the arm or thrusts of the tooling operation, that may be easily constructed, relatively light in weight and considerably smaller in proportion than a cast iron column of equal capacity.

In attaining that object it is proposed to construct the column of steel plate and tubing, previously cut to the required shapes and sizes, and welded together at their joints. A steel column fabricated and welded, as herein proposed, is, as compared with a cast column of equal size, at least 30% stronger. The net result being that a fabricated welded column may be constructed considerably smaller than a cast column for the corresponding service, lighter in weight, and consequently more easily machined and handled. Moreover, with a fabricated welded column, expensive patterns and losses due to defective castings are entirely eliminated.

A further object of the invention is to pro-

vide a column which in its roughest condition requires but a minimum amount of tooling to convert it into a finished product ready for installation in a machine tool organization. That end is readily achieved in this fabricated welded column construction for the reason that the steel plate and tubing selected for the column is of standard uniform thickness and sizes having relatively finished surfaces. The only machining necessary to the fabricated column being that around the bearings and the external welds. As these portions to be machined are relatively few and small in number and area the whole column may be constructed and installed in a machine tool in a fraction of the time and expense heretofore involved in the construction of cast columns.

Still another object of the invention is to provide a column amply reenforced at the critical points. In radial drill columns the crucial region wherein the largest portion of the bending stresses fall, is at the lower end thereof just above the base. With the cast columns heretofore used, manufacturers have endeavored to reinforce that area of the column by the use of ribs, etc., which fall far short of giving the strength and rigidity required. Problems arising in the foundry also presented insurmountable obstacles in the proper design of cast columns.

A fabricated welded steel column, however, renders possible a structure conceived along scientifically and mathematically sound lines and in which adequate provision may be made for all the factors of load, stresses, and safety.

In carrying out the objects of this invention it is proposed to weld a relatively short sleeve member to a base plate of the desired size, and to the top thereof weld an annular inwardly extending flange or bearing ring. A relatively long length of steel tubing forms the column proper and to the bottom of which there is welded a transverse plate which closely fits the inside of the lower sleeve portion. By inserting the top end of the column proper through the lower sleeve and the annular flange from the under side, a telescoping structure is formed by means of which the column may, within certain limits, be adjusted for height. After the proper height of column is obtained the two portions are welded together as an integral unit thereby forming a complete column, reenforced at its lower end by the bi-tubular construction. This design lends support to the upright post at all sides of its extreme lower end and also to a region substantially removed therefrom, thus effectively resist-

ing the forces tending to bend or deform the column at that critical region.

The present invention it will be observed also renders available a column free of internal longitudinal or radial ribs and webbings and in which there is ample free space available for the insertion of gears, shafting and such other mechanisms as may be desired.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 is an assembly view of a typical radial drilling machine embodying this invention.

Fig. 2 is a vertical sectional view of a preferred form of welded steel column.

Fig. 3 is a side elevational view the lower portion of the column wherein provision is made for the convenient insertion of power lines or other mechanisms.

Fig. 4 is a horizontal sectional view along lines 4—4 of Fig. 2.

Referring more particularly to Fig. 1 of the drawings the typical machine therein illustrated comprises essentially a base member 10; an upwardly standing post or column 11 secured thereto; a sleeve member 12 rotatable upon the post; a radially extending arm member 13 vertically adjustable upon the sleeve; and a tool head 14 translatable on the arm, toward or away from the main supporting column.

Within the tool head 14, a tool spindle 15 is journaled for rotation and translation, and also all the mechanism necessary for driving the spindle at various speeds and for translating the head on the arm. In certain types of constructions the arm also supports a main driving motor 16, while in other constructions the drive motor is located at the base of the column.

The main characteristic of a radial drill is the ability to drill to the center of very large work-pieces and to that end machines are made with an arm projecting 10 to 12 feet from the column. This great overhang of the arm sets up enormous bending stresses in the post 11 at the region indicated upon the drawings. The stresses are, of course, more severe when the head is at the extreme end of the arm than when the head is near the column. However, with either condition any bending or yielding of the column, whether caused by the load of the arm or by the thrusts of the tooling operation, is greatly magnified and visually apparent at the drill spindle, resulting not only in inaccurate work but in work being spoiled because of the tendency of the drill to break through the work near the end of the cut due to the reflex spring in the column.

To overcome the disadvantages above indicated it is proposed to fabricate a column of steel plate and tubing. Fig. 2 illustrates in section, a preferred method of constructing an eminently rigid column devoid of the flexing characteristics displayed in columns heretofore designed. The present column is constructed of two main parts, a base member 20 which is bolted to the floor or to the main base of the machine, and an upright

cylindrical post 21, a substantial portion of which telescopes within the outer shell portion 20.

The post 21 is preferably made of steel and is capped with a bearing and supporting plate 22, welded thereto as indicated at 23. The center of the cap 22 is initially provided with an aperture 24 for receiving radial and thrust bearings for suspending the weight of the sleeve 12 and all parts carried thereby. The lower end of the hollow post or shell 21 has welded thereto a plate 10 member 25 which extends beyond its periphery into engagement with the inner wall of the base portion 20.

A preferred form of a base for rigidly supporting the steel post 21 comprises a base-plate member 28 of a size sufficient to provide a peripheral bolting flange. The central section of the base-plate may be cut away and notched as at 29 to provide respectively a space for enclosed mechanism and a gate for the insertion of same.

Extending upright from, and welded to the base-plate 28 is a cylindrical sleeve member 30 which completely encircles the post-plate 25 and provides an exterior clamping surface for the sleeve 12. Prior to welding the cylindrical member 30 to the base-plate 28, a reenforcing annular band 31 is welded thereto as at 32 and 33. The weld 32 is thereafter ground smooth and the sleeve 30 with its reenforcing band 31 welded to the base-plate 28 as at 34 and 35.

The top of the sleeve 30 has welded thereto, inside at 40 and outside at 41, a stepped plate 36, the center of which is apertured at 37 to receive the steel inner tube 21 and to support same against lateral movement.

In assembling the post to the base, the post is inserted from the bottom through the opening 31, adjusted vertically therein until the proper height is obtained and welded at 38 and 39. Preferably this height should be such that the lower post flange 25 comes within the bounds of the reenforcing band 31, so that the lateral thrusts reacting at the lower end of the post 25 are resisted not only by the sleeve 30 but also by the band 31.

To complete the column a bearing band 42 is welded to the post 21 at the required height, and a cover member 43 welded to the base-plate 28 and reenforcing band 31, for covering the gateway to the open space within the column.

In the machine illustrated the bearing band 42 is ground true and cooperates with complementary bearings means provided in the sleeve 12. The sleeve is thereby guided against any lateral movement relative to the post 21 but may rotate thereon and be clamped in any angularly adjusted position by the clamp means indicated at 50. To prevent the enormous weight of the overhanging arm from impinging the sleeve tightly on the surface of the bearing member 42 and outer shell member 30, adjustable anti-friction rollers 44 journaled in the bell portion of the sleeve 12, are provided. The rollers 44 ride against the periphery of a bearing ring 51 seated in the step 45 in the plate 36.

After assembling and welding the plates and cylinders together as above explained the column is ready for finishing the surfaces of the bearing members 42 and sleeve clamping member 30. Inasmuch as these parts already are provided with relatively smooth and true peripheries, the expense involved in bringing them to the precise dimension required is reduced to a minimum.

From the foregoing it will be perceived that a welded steel column is rendered available having

all the advantages of a cast column plus the additional advantages of being smaller in size, more sturdy and rigid in the vital regions, and easily and quickly constructed. All vertical thrusts on the post 21 are transmitted to the base at two regions, namely through the plates 25 and 36. The rectangular section defined by the walls of these plates and the side walls of the cylinders 21 and 30 affording a closed rectangular annulus 10 eminently suited to resist any vertical or lateral deflection under the lever action of the arm incident to its weight or occasioned by the tooling thrusts. The post 21 being a steel substantially heavy-walled tube, both ends of which are reinforced by the welded caps 25 and 22, of itself effectively resists the enormous collapsing strains to which it is subjected.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims:—

Having thus revealed this invention, I claim as new and desire to secure the following combinations and elements, or equivalents thereof, by Letters Patent of the United States:

1. A radial drill combining a base, a horizontally disposed arm member extending in parallel spaced relation with said base; a tool head, having a tool spindle journaled therein, translatable on the arm; and a vertically arranged welded steel column connected with one of said arm and with said base for supporting said arm and for maintaining same in said parallel spaced relation under the reactionary forces of the tooling operation and of gravity, comprising a relatively long inner steel shell and a relatively short outer steel shell arranged in spaced relation and partially telescoped, the lower end of said outer shell extending beyond the lower end of said inner shell, and a pair of spaced flange members arranged transverse to the axis of said shells for connecting said shells together as an integral unit 50 and for transmitting to said outer shell the vertically and laterally acting forces of the inner shell incident to the weight and lever action of the said arm acting thereon.

2. A radial drill combining a horizontally extending arm member; a tool head translatable on the arm; a tool spindle journaled in said head; an upright column member for supporting one end of said arm and for maintaining said arm in said horizontal relation under the reactionary forces of gravity and of the tooling operation, comprising an upright steel post member, a supporting base member for said post overlapping the lower portions of said post and extending beyond the end thereof, said base member having an aperture provided therein for receiving a substantial portion of the lower end of said post member, and means arranged perpendicular to the axis of said post integrally connecting the extreme lower end of said post member to an intermediate section of said base member and the top of said base member to an intermediate section of said post.

3. A radial drill combining a base member; a fabricated tubular column member uprising therefrom; an arm member supported by and

extending radially from said tubular column; said column comprising a smooth walled steel tube having at its lower end a concentric peripherally spaced sleeve member, said sleeve member extending beyond the end of said tube; a pair of spaced flange members integrally welded to said sleeve, one of the flanges being adjacent the extreme lower end of said steel tube and the other of said flanges being adjacent the top of said sleeve and engaging the outer periphery of an intermediate section of said tube; and means uniting said flanges, steel tube and sleeve members together as an integral unit affording a bi-tubular reenforced column construction, having at least one annular and completely closed cell, resisting bending strains occurring at the lower portions thereof incident to the weight and lever action of said arm.

4. A radial drill combining a base; an arm member spaced therefrom and in parallel relation therewith; a column member for rigidly supporting one end of said arm, comprising a hollow steel tubular member, a concentrically arranged spaced sleeve member adjacent one end of said steel tubular member and extending beyond the end thereof, a first transverse flange member connecting the end of said tubular member with the inner periphery of said sleeve member intermediate its ends, a second transverse flange member connecting the upper end of said sleeve member with the outer periphery of an intermediate section of said tubular member, said transverse flanges being spaced apart from one another forming a closed annular cell between said sleeve and tubular member, for supporting the end and intermediate regions of said tubular member against vertical and lateral movement; and means encircling said sleeve member at a region coincident with the plane of one said transverse connecting flanges for reenforcing said sleeve against the laterally acting strains transmitted through the said flange.

5. A radial drill combining a base member; a fabricated tubular column member uprising therefrom; an arm member supported by and projecting radially from said tubular column; said column comprising a smooth walled steel tube, a concentrically arranged open ended sleeve member surrounding the lower portion of said tube and extending beyond the end thereof, an annular flange engaging the upper end periphery of said sleeve and the periphery of said tube at a point intermediate its ends, a second annular flange member engaging the lower end of said tube and the adjacent inner wall of the said sleeve member, said flanges, steel tube and sleeve members being welded together as to form an integral unit having a closed rectangular annular space between said flanges, tube, and sleeve, and adapted to withstand the vertical lateral strains incident to the weight and lever action of the said projecting arm, and a metal ring member encircling the lower portion of said sleeve and welded thereto for additionally reenforcing same.

6. A radial drill combining a base, an arm member extending in parallel spaced relation with said base; a tool head, having a tool spindle journaled therein, translatable on the arm; and a column connected with one end of said arm and with said base for supporting said arm and tool head and for maintaining said arm in said parallel spaced relation under the reactionary forces of the tooling operation and of gravity, comprising a relatively long inner steel shell and a relatively short outer shell arranged concen-

- trically and in spaced relation, and a pair of vertically spaced continuous flange members arranged transverse to the axis of said shells, said flange members and said shells being welded together as an integral unit with the lower end of said inner shell spaced from said base and for transmitting to said outer shell the vertically acting forces of the inner shell induced by the weight of said arm, said concentric shells and spaced flanges forming a closed rectangular annulus about the lower portion of said inner shell for resisting the lateral strains set up in the lower portion of the column incident to the lever action of said arm.
15. 7. A radial drill combining a horizontally extending arm member; a tool head translatable on the arm; a tool spindle journaled in said head; a column member for supporting one end of said arm and for maintaining said arm in said horizontal relation under the reactionary forces of gravity and of the tooling operation, comprising an upright steel post member connected with one end of said arm, a supporting base member for said post, said base member having an aperture provided therein for receiving a substantial portion of the lower end of said post member, and having flange means arranged in spaced relation in parallel planes perpendicular to the axis of said post and adapted to engage the extreme lower end and an intermediate section of said post, said flanges and post members being welded integrally together thereby affording a rigid bi-tubular column member reenforced at its lower end against lateral strains incident to the lever action of said arm.
8. A radial drill combining a base member; a fabricated tubular column member uprising therefrom constituted of a plurality of concentrically arranged tubular portions welded to-

gether, the outer portion extending only part way to the top of the inner portion and exteriorly providing a clamping surface and interiorly connected to the inner portion by a plurality of horizontally disposed flanges, one of said flanges being adjacent the lower end of the inner portion and another of said flanges being adjacent the top of said outer portion; a sleeve member surrounding both of said portions and having its lower end adapted to be constricted in clamping relation with said clamping surface; an arm member extending radially from said sleeve and arranged for vertical movement thereon, said welded tubular portions and flanges affording a rigid column member reenforced against vertical and lateral thrusts of said sleeve incident to the weight and lever action of said arm.

9. The method of fabricating a steel column from steel plate and tubing for a radial drilling machine which consists in welding a circular flange plate member to the end of a length of smaller diameter steel tubing, welding an inwardly projecting annular flange plate member to one end of a shorter length of steel tubing which has an inside diameter approximately equal to the diameter of the flange plate welded to the first mentioned steel tube, placing said two steel tubes in telescoped relation with the flanged end of the first mentioned tube inside of the second steel tube and spaced from the inwardly projecting flanged end thereof, and with the inner edge of the inwardly projecting flange adjacent the outer periphery of the first mentioned steel tube, and then welding the adjacent portions of both flanges and steel tubes thereby to provide a bi-tubular steel column reenforced by the two transverse spaced flanges.
